UNITED STATES PATENT OFFICE

MAXIME CHAPUIS, OF CHICAGO, ILLINOIS

DESIGN FOR A SMOKER'S STAND

Application filed October 2, 1931. Serial No. 41,296. Term of patent 7 years.

To all whom it may concern:

Be it known that I, MAXIME CHAPUIS, a citizen of France, but domiciled within the United States, and residing at Chicago, in the county of Cook and State of Illinois, have invented a new, original, and ornamental Design for a Smoker's Stand, of which the following is a specification, reference being had to the accompanying drawing, forming a part thereof.

Fig. 1 is a front plan view;
Fig. 2 is a side view in elevation; and
Fig. 3 is a top plan view.

I claim:

The ornamental design for a smoker's stand, as shown.

MAXIME CHAPUIS.
